UNITED STATES PATENT OFFICE.

LEE S. ANDERSON, OF DETROIT, MICHIGAN.

DEVICE FOR TURNING SHEET-MUSIC.

1,328,976.

Specification of Letters Patent. Patented Jan. 27, 1920.

Application filed September 15, 1919. Serial No. 323,690.

To all whom it may concern:

Be it known that I, LEE S. ANDERSON, a citizen of the Dominion of Canada, subject of the King of Great Britain, residing at 5 Detroit, county of Wayne, State of Michigan, have invented a certain new and useful Improvement in Devices for Turning Sheet-Music, and declare the following to be a full, clear, and exact description of the same, 10 such as will enable others skilled in the art to which it pertains to make and use the same, reference being had to the accompanying drawings, which form a part of this specification.

15 My invention relates to a device for turning sheet music. It is particularly designed for use in connection with a piano or organ, or other musical instrument having an upright music stand. The device is operated 20 by foot from a pedal and is designed to allow the musician to be free at all times. The device as here shown is illustrated in conjunction with the music rack of a piano or organ. It is understood, however, that 25 the device is not claimed merely for use in conjunction with such instrument.

In the drawings,

Figure 1, is a front elevation of the music rack showing the device attached thereto. 30 Fig. 2 is a rear elevation of the music rack showing the device attached thereto.

Fig. 3 is a cross-section partly broken away, taken on line III—III of Fig. 1.

Fig. 4 is an enlarged elevation of guide 35 plate shown in Fig. 1.

Fig. 5 is a cross-section taken on the line V—V of Fig. 3.

The music rack 2 is recessed longitudinally, as shown at 3. This recess is 40 formed so as to provide a path or way for the longitudinal movement of guide plate 1, the outer surface of such guide plate being flush with the surface of the music rack. The guide plate is held in place by means of 45 a strip or clip 3^a. Affixed to the rear of the guide plate is a rack extending longitudinally thereof at approximately the central portion designated as 4. This rack is designed to mesh with a pinion 5 carried at 50 the upper end of the shaft 6, said shaft being disposed in bearings 7, 7. The lower end of this shaft is provided with a bevel gear 8 which meshes at right angles with the bevel gear 9. Bevel gear 9 has at the oppo-

site end the shaft 10, upon which it is 55 mounted, a foot pedal 11. This foot pedal 11 is so disposed as to be easily operated by the musician. This particular arrangement of bevel gears and shafts might be varied 60 to meet particular designs of instrument 65 with which the attachment is used. It will be seen that the operation of the foot pedal 11 serves to permit motion from the shafts and gears heretofore described to guide plate 1 as the pinion 5 meshes with the rack 4 carried by said guide plate; therefore the 70 operation of the foot pedal a predetermined distance will move the guide plate a predetermined distance within the recess 3 of the music rack. The face of said guide 75 plate 1 is provided with a series of racks extending longitudinally thereof in successive parallel planes designated in Fig. 4, as 12, 13 and 14. Alternating with these racks and of slightly greater altitude, the 80 ends of which somewhat overlap the ends of the racks, are guide rods 15, 16, and 17 for purposes hereafter described.

There is provided on the front of the music rack brackets 18 and 18^a carrying 85 shaft 19 upon which shaft are freely mounted pinions 20, 21, and 22. These pinions are held in spaced relationship one from the other by means of bushing or pinion hubs and are designed to mesh with 90 racks 12, 13 and 14 respectively. It will be observed that the music rail is cut away in the rear of such pinions, as at 23, so as to permit the engagement of the pinions with the racks carried by the guide plate. Affixed 95 radially to pinions 20, 21, and 22 are arms 24, 25 and 26. These arms are offset at their outer extremities so that the extremities will lie in substantially the same horizontal plane and will overhang the sheet music 100 carried on the rail of the rack. These arms are likewise of varying lengths so there will be no conflict in the individual movement thereof. The outer extremities of these radially-extending arms are provided with 105 clips 24^a, 25^a and 26^a adapted to grip the sheets of music intended to be operated by this device. It is apparent that the number of pinions and therefore the number of radially-extending arms may be increased, 110 if so desired. Carried by pinions 20, 21, and 22 are stops 27, 28 and 29 which are adapted to be engaged by the guide rods 15,

16 and 17 respectively when the pinions are revolved what amounts to substantially 180 degrees.

5 The operation of my above-described device is as follows:

As the foot pedal 11 is actuated by the operator it transmits motion through shaft 10, bevel gears 9 and 8 which in turn rotate shaft 6 and pinion 5 which meshes with the 10 rack 4 carried on the rear of guide plate 1. This serves to move the guide plate longitudinally in the slot 3 of the music rack a predetermined distance. When the guide plate 1 is in the position shown in dotted 15 outline in Fig. 1 such movement will cause the rack 14 to mesh with the pinion 22 and rotate the same, which in turn would actuate the arm 26, turning the sheet music held in the finger clip 26^a.

20 It will be observed that guide rod 17, in a plane parallel to but offset from the rack 14 and of higher altitude will come in contact with the stop 29 carried by pinion 22 before the rack and pinion are out of mesh. 25 This would engage the stop 29 carried by pinion 22 and will hold the pinion from revolving so as to hold the arm 26 in position after the sheet of music has been turned. Continued successive operations will produce 30 similar results through the engagement of the other racks and pinions shown in the drawings.

It will be observed that the mechanical movements of this device are all direct ones 35 and that there are no springs or bands to get out of order and that the device is one of simple mechanical combinations.

Claims:

1. In a music rack provided with a longitudinal recess, a guide plate seated in said recess for longitudinal movement, means for holding the same in position, means for operating said guide plate longitudinally within said recess from a foot pedal, the 40 pedal, a series of racks disposed successively in parallel planes carried by the face of said guide plate, a series of pinions held in spaced relationship from each other freely mounted on a shaft, adapted to mesh with the said 45 racks carried on the face of said guide plate, radially-extended arms carried by said pinions provided with gripping fingers to grip sheets of sheet music and offset to overhang sheet music disposed on the rail of the music 50 rack, a series of guide rods alternating with said racks and of higher altitude than said racks and slightly overlapping the ends thereof, stops carried by said pinions and perpendicular thereto, said stops adapted to 55 engage said guide rods which alternate with said racks so as to limit the movement of said pinions.

2. In a music rack, a longitudinally recessed slot, a guide plate disposed for longitudinal movement seated in said slot, means

for holding the same in position, a rack carried at the back of said guide plate adapted to mesh with a pinion, such pinion, means for driving such pinion from a foot pedal, said pedal, a series of successively disposed parallel racks carried on the face of said guide plate, pinions adapted to mesh with said racks through an opening in said music rack, a radial arm carried by each of said pinions offset to overhang the sheet 75 music carried on the rail of said music rack, said arms being of successive lengths, gripping fingers carried by said arms for holding sheets of sheet music to turn the same as the pinions are rotated by coöperating 80 with the racks, stops carried by said pinions, rods carried by said guide plate adapted to be engaged by said stops to limit rotation of said pinions.

3. In a device for turning sheet music, a 85 music rack provided with a longitudinal recess, a guide plate seated in said recess and adapted for longitudinal movement therein, means for operating such guide plate, a series of racks carried on the face of said 90 guide plate longitudinally thereof, disposed in successive parallel planes, a series of pinions carried on the face of said music rack, each of said pinions adapted to engage a rack carried on the face of said guide plate, 95 a radial arm carried by each of said pinions extended to overhang the sheet music, gripping fingers, one provided for each arm adapted to grip the sheets of sheet music to turn the same as the arm rotates about 100 the axis of the pinion, means for limiting the rotation of said pinions.

4. In a device for turning sheet music, a music rack longitudinally slotted to provide a seat for a guide plate, a guide plate 105 positioned in said slot and adapted for longitudinal movement therein, means for holding said guide plate in position, a rack on the back of said guide plate, a pinion meshing with said rack, means for operating 110 said pinion, a series of racks carried on the face of said guide plate disposed in successive spaced parallel planes, a pinion meshing with each of said racks, an arm carried radially on each of said pinions offset so 115 that the outer extremity lies in substantially a horizontal plane, gripping fingers carried by said arms, to grip the sheets of sheet music, stops on said pinions, means for engaging said stops to limit the rotation of 120 said pinion as each pinion runs out of mesh with its coöperating rack.

5. In a device of the class described, a guide plate adapted for horizontal movement, a rack carried by said guide plate, 125 means for driving said guide plate through said rack from a foot pedal, a series of racks disposed in successive parallel planes on the face of said guide plate, pinions disposed to mesh with said racks, arms carried 130

5 by said pinions provided with means for engaging sheets of sheet music, means for engaging each individual pinion after it has been rotated and just as it passes out of mesh to prevent further movement thereof.

6. In a device of the class described, a 10 guide plate adapted for horizontal movement, means for driving said guide plate, a series of racks disposed on the face of said 15 guide plate in parallel successive planes, arms provided with gripping members for engaging sheets of sheet music pivoted for rotation and adapted for engagement each with an individual rack, means for holding each of said arms in its new position after the sheet of music has been turned and until the guide plate has been reciprocated.

7. In a device of the class described, a 20 movable guide plate, means for driving the same, a series of racks disposed on the face of said guide plate in stepped relationship one to the other, a series of rods of slightly greater altitude than said racks disposed as 25 offset continuations thereof, a series of pinions mounted for separate engagement with individual racks, radial arms carried by said pinions, means carried by said arms for engaging individual sheets of sheet music, a stop carried on each of said pinions adapted 30 to engage the rod which serves as an offset continuation of the rack which is positioned to engage said pinion.

In testimony whereof, I sign this specification.

LEE S. ANDERSON.
